(57) **CLAIM**

The ornamental design for a motorcycle handlebar cover, as shown and described.

DESCRIPTION

FIG. 1 is a top perspective view of the motorcycle handlebar cover of the present invention.

FIG. 2 is a top side view thereof.

FIG. 3 is a bottom side view thereof.

FIG. 4 is a right side view thereof.

FIG. 5 is a left side view thereof.

FIG. 6 is a first end view thereof; and,

FIG. 7 is a second end view thereof, opposite the first end view.

The top surface portions and rear surface of the motorcycle handlebar cover shown in broken lines form no part of the claimed design.
